UNITED STATES PATENT OFFICE.

WILLIAM H. HOOPER AND FRED S. HUTCHINS, OF SAN FRANCISCO, CALIFORNIA.

EXPLOSIVE-ENGINE.

No. 876,878.

Specification of Letters Patent.

Patented Jan. 14, 1908.

Application filed December 19, 1905. Serial No. 292,427.

To all whom it may concern:

Be it known that we, WILLIAM H. HOOPER and FRED S. HUTCHINS, citizens of the United States, residing at San Francisco, in the county of San Francisco and State of California, have invented certain new and useful Improvements in Explosive-Engines, of which the following is a specification.

This invention relates to gas engines of the two-cycle type, in which during a single revolution of the engine shaft, the piston goes through the movements which result in compression of an explosive mixture, a power stroke as a result of the explosion of the compressed mixture, the clearance of the cylinder from the burned charge, and the readmission of a fresh charge of the explosive mixture.

The invention is in some respects an improvement upon that shown in an application of William H. Hooper and Fred S. Hutchins filed April 28, 1905, No. 257,888, in that the construction has been considerably simplified and in addition the principle of the invention has been shown in the present case as applied to a multiple cylinder engine, although of course equally applicable to a single cylinder engine as is also shown.

The object of the invention is to produce a high or low speed engine of relatively high power, of simple construction, and of relatively light weight.

The invention is illustrated in the accompanying drawings in which;

Figure 1 is a sectional side elevation of a four cylinder engine containing the present invention; Fig. 2 is a top plan of the same; Fig. 3 is a horizontal section through three of the cylinders in accordance with the relative positions of the cylinders in Fig. 1; Fig. 4 is an enlarged vertical section of a single cylinder taken at right angles to Fig. 1; Figs. 5, 6, 7, and 8 are sections of a single cylinder illustrating progressively a single revolution of the crank shaft and the different positions assumed by the various parts during such revolution.

The engine is supported by any suitable bed an indication of which is shown in Fig. 4 and which may be of any preferred design. The engine supported upon this bed is built up in three main parts, the crank-case 1, the slide box 2, and the cylinder 3. For convenience in description the engine will first be described as if it were a single cylinder engine with subsequent reference to a multiple

cylinder construction, in which each separate cylinder and its piston properly timed as to its stroke performs the same function. The actual construction of the engine will be best understood from Fig. 4 which is much enlarged as compared with the other views and to which at present reference is principally made. The crank case is shown as provided with interior ribs 4 spaced at proper distances apart as shown in Fig. 1, in which are bearings for the engine shaft 5. End extensions 6 of the crank case provide the end bearings for said shaft. The crank case is bolted to the slide valve chamber 2 as shown at 8 in Fig. 1. The crank is jointed to its connecting rod 9, and the rod to the piston 11, which has a closed lower end.

The slide valve chamber 2 is provided with an interior renewable wearing plate 12, upon which the valve 13 slides. This valve is, for convenience in forming the central spherical ball seat as well as for receiving the ball 14 made preferably in two parts as shown. The ball 14 is bored out vertically, and this bore is partly enlarged to admit the stuffing box 15, and compression screw 16. The connecting rod passes through the bore of the ball, the stuffing box and the screw, and the oscillation of the rod will cause a horizontal reciprocation of the slide valve, which opens and closes an inlet 17 from the gas supply passage 18 to the cylinder below the piston. The square base 19 of the cylinder is secured to the slide-valve chamber by corner bolts 21, as shown in Fig. 3.

The exhaust arrangement will be understood by a comparison of Figs. 3, 4 and 7. Referring first to Fig. 3 and to the second cylinder from the left, which for the present part of the description may be considered as a single engine, it will be seen that an exhaust passage 22 is formed with the inner wall of the cylinder, which communicates with the interior of the latter by means of openings 23, and such openings are also shown in Fig. 7. These openings when uncovered by the piston on its downward movement receive the burned charge which escapes from the cylinder. The fresh charge which, as before stated has been admitted below the piston from the passage 18, is expelled by the same downward movement which opened the exhaust passage into the passage 24. The communication between the interior of the cylinder and this passage is normally closed by the spring-seated valve 25; and the fresh

charge is forced into the passage 24, before the exhaust is opened, as shown in Fig. 6. The passage 24 communicates with a perforated cage 26, shown in Fig. 4; and also in the 5 left hand engine of Fig. 3. At the bottom of this cage is a valve seat, and a valve 27, controlled by a spring which tends to close it. The ignition of the compressed charge in one cylinder or in a plurality of cylinders, is controlled by the engine shaft. This shaft has 10 fixed upon it a sleeve 10 which carries the yielding contact 20. As many stationary contacts 30 as there are cylinders are carried by and insulated from the engine frame. 15 Two of such contacts are shown in Fig. 1, and three in Figs. 2 and 3, there being four in all in the four cylinder engine illustrated. Any suitable source of electricity is connected by wires 40 to the stationary contacts. 20 Having substantially described the construction of the engine the operation will now be referred to, with particular reference to Figs. 5 to 8 inclusive. It has been described how the charge admitted beneath the piston 25 is forced into the passage 24 and thence through the perforated cage above the piston. Fig. 5 therefore shows the piston at its highest point, closing the upper inlet valve and compressing the charge. The jump 30 spark is formed between the electrodes 28 and 29 in the screw plug 31. This plug is screwed into the passage 32, which communicates with the interior of the cylinder above the highest position of the piston; as 35 best shown in Fig. 4. When the piston has reached its highest point and has compressed the charge, the jump spark causes the explosion and drives the piston downward as shown in Fig. 6. There being a fresh charge 40 beneath the piston as heretofore explained, such charge is forced into the passage 24, past the opened valve 25. This accounts for one quarter of the revolution of the engine shaft. As the piston continues its down- 45 ward movement the exhaust passages are opened as shown in Fig. 7. As soon as the cylinder has started to exhaust and the pressure in the cylinder is a little less than the pressure in the chamber 24 the gas from the 50 chamber 24 through the valve 27 comes in and forces out the burnt gases in the cylinder, and that gas is compressed and exploded as the piston comes up into the top as shown in Fig. 5, while at the same time it permits the 55 opened slide valve inlet to admit a new charge beneath the rising piston. The simplicity of this construction will be apparent at once to those skilled in the art. Now, if the construction be applied to a multiple cylinder engine, each engine acts in the manner 60 before described. Referring to Fig. 1, a single crank-case underlies the four cylinders shown, and it is because the invention is adapted to a multiple cylinder engine that 65 the crank case is provided with strengthen-

ing rib-work which provides separated bearings for a long engine shaft as shown in Fig. 1. Indeed Fig. 1 has been drawn to show different positions of the piston which will correspond to the positions shown in Figs. 5, 6, 7 and 8. So that Figs. 5, 6, 7, and 8 showing the action of one cylinder and piston through the two-cycle movement, illustrate the action of the four cylinder engine shown in Figs. 1, 2 and 3. The action of each cylinder of the multiple cylinder engine of Figs. 1, 2, and 3 is the same as that of the single cylinder shown in Fig. 4; but it is to be noted that there is a single crank case beneath all the cylinders, and a single engine shaft with 80 cranks in quartered positions, so that a single revolution of the engine shaft will produce in each cylinder and in proper time, the proper successive movements of the several pistons to produce the compression, admission of the charge beneath each piston, explosion, exhaust, and admission of the fresh charge above the several pistons, so that from a single engine shaft, the proper successive movements are derived from all the 90 cylinders.

Referring to Figs. 2 and 3; in those Figures are shown a main gas inlet 35, leading into a header 36 which communicates with the passage 18 which supplies gas below and 95 through the slide valve, the supply to the several cylinders being controlled by the quartering cranks through the several slide valves.

From each exhaust space 22, a branch 37 leads into a common exhaust passage 38 which leads to the open air through any kind of muffler, if it be desired to use such a muffler.

We do not limit ourselves to the specific 105 details of construction herein described and shown in the drawings, as we desire to avail ourselves of such modifications and equivalents as fall properly within the spirit of the invention.

Having thus described my invention, what I claim as new and desire to secure by Letters Patent, is:—

1. In a gas engine, an engine frame or structure comprising a crank case, a separately formed slide valve chamber secured to the crank case, and a cylinder secured to the slide valve chamber; said three parts being in longitudinal alinement, with said valve chamber in the intermediate position. 115
2. In a gas engine, a crank-case, an engine cylinder, a slide-valve chamber between the crank-case, and cylinder, such parts being secured rigidly together, a gas inlet passage opening into the slide-valve chamber, a slide-valve in said chamber, a crank shaft, a connecting rod, a ball seated in the slide-valve and through which such connecting rod passes, a piston, a passage from the lower 125 part of the cylinder to the upper part of the 130

cylinder, a valve controlling the exit of fresh gas from the lower part of the cylinder to the said passage, and a valve controlling the admission of gas to the cylinder above 5 the piston.

3. In a gas engine, a crank case, slide-valve chamber, slide-valve and cylinder, a piston, a connecting rod passing through the slide-valve and operating the same by 10 its oscillation, a gas inlet to the cylinder beneath the piston, and an exhaust outlet in the cylinder adapted to be opened by the piston when at the lower extremity of its stroke.
- 15 4. In a two-cycle gas engine, a gas inlet for admitting gas beneath the piston, a slide valve controlled by the connecting rod for opening and closing said inlet, an outlet leading into the cylinder above the piston, 20 and an exhaust outlet from the cylinder opened by the downward motion of the piston and closed by its upward motion.

5. A multiple cylinder engine, having a crank-case beneath and common to all the cylinders, a crank shaft passing through the 25 crank-case and having bearings therein, cranks on said shaft located relatively to the respective cylinders so as to cause their respective pistons to control the inlet, compression and exhaust, progressively, a slide 30 valve for each cylinder operated by its connecting rod, inlet openings to said cylinders from a common inlet pipe, and exhaust outlets from said cylinders to a common exhaust pipe.

35

In testimony whereof we affix our signatures, in presence of two witnesses, this eighth day of December 1905.

WILLIAM H. HOOPER.
FRED S. HUTCHINS.
